UNITED STATES PATENT OFFICE.

AUGUST NOGAR, OF READING, PENNSYLVANIA, ASSIGNOR OF ONE-EIGHTH TO GEORGE JAKABCIN AND ONE-EIGHTH TO JOHN JAKABCIN, BOTH OF READING, PENNSYLVANIA.

NON-SINKABLE SHIP.

1,119,715.

Specification of Letters Patent.

Patented Dec. 1, 1914.

Application filed May 28, 1914. Serial No. 841,488.

To all whom it may concern:

Be it known that I, AUGUST NOGAR, a citizen of the United States, residing at Reading, in the county of Berks and State of Pennsylvania, have invented certain new and useful Improvements in Non-Sinkable Ships, of which the following is a specification.

This invention relates to non-sinkable ships, and one of the principal objects of the invention is to provide air containers or receptacles to be placed at opposite sides of the ship to prevent careening or capsizing of the boat and at the same time to prevent the boat from rocking longitudinally and also from sinking.

Another object of the invention is to provide a series of air containers on opposite sides of the ship, said containers each comprising a series of partitioned compartments for containing air, so that should one of the compartments be punctured or injured, it will not interfere with the function of the remaining compartments.

Still another object of the invention is to provide a series of air containers at opposite sides of the boat made up in sections of various compartments extending a certain length longitudinally at the side of the boat, said sections being separated by partitions or bulk heads, so that should one section of the boat become injured it will not interfere with the buoyant qualities of the remainder of the boat.

These and other objects may be attained by means of the construction illustrated in the accompanying drawings, in which—

Figure 1 is a side elevation of a ship provided with air containers made in accordance with this invention. Fig. 2 is a transverse sectional view of the ship showing upon one side the air containers in place, and upon the other side the manner of constructing the partitions and bulk heads, and Fig. 3 is a detail sectional view showing the manner of securing the air containers to the deck and side partitions of the ship.

Referring to the drawings, and more particularly to Fig. 1, the numeral 1 designates a ship, in which the opposite sides are extended to form spaces for the air containers, and as shown in this figure, the vertical lines 2 represent the partitions or bulk heads which separate the air container sections, one from the other. It is to be noted that toward the bow of the boat, the partitions

or bulk heads 2 are quite close together and that they gradually increase in length toward the stern of the boat. The purpose of this arrangement is, in order to meet the usual contingencies in sea travel, it has been found that the greater majority of accidents to ships involve the injury of the bow or that locality from the bow of the boat back toward the quarter in a greater number of instances than from the center of the boat to the stern, hence, the forward or bow portion of the boat is provided with comparatively short compartments for the series of air containers, so that if one should be injured it would not interfere with the function of the next adjacent, etc.

Referring now to Fig. 2, in which a transverse vertical sectional view is shown, the side portions 3 of the boat or vessel are occupied by a series of air containers 4, which practically fill up the entire space of the side portion 3 of the boat or vessel. The air containers 4 are made up by means of an enlarged casing provided with a top 5, a side 6 upon the outside, and a side wall 7 on the inside, and in order to hold the air containers in place, a suitable fastener or bolt 8 extends through the deck 9 into one of the containers upon the top row which are designated by the numeral 10, while at the inner upper corner, the container is also connected to the side partition 11 by means of a suitable bolt 12, and each of the containers 13 may be also secured by a similar bolt or fastening to partition 11.

The partitions or bulk heads are formed by means of braces 18 and vertical supports 19, while the bulk heads are fitted against these braces and secured firmly in place by rivets or other suitable means.

As shown in dotted lines in Fig. 2 on opposite sides, inside the projecting side portions 3 spaces may be utilized to be filled with air containers as indicated at 20, thus leaving sufficient space in the center for the various decks, and for machinery, boilers or other articles required. The decks 21 may be of any required height, one from the other, while the upper decks 22 may extend entirely over the air containers at opposite sides of the ship.

From the foregoing it will be obvious that a ship made in accordance with this invention cannot readily sink, will ride the waves nicely, will not tip from one side to the

other owing to the fact that the air containers are upon opposite sides of the ship, and that the ship cannot tilt and heave longitudinally owing to the projection of the sides which contain the air compartments.

Various changes may be made in the details of construction without departing from the spirit and scope of the invention as defined in the claim.

10. What is claimed is:

The herein-described ship provided with side extensions, air containers inclosed within said extensions, said air containers com-

prising rectangular compartments secured by fasteners to the deck and partition, and said containers being arranged in sections, and bulkheads for dividing said sections, said bulk heads comprising diagonal and vertical brace bars.

In testimony whereof I affix my signature in presence of two witnesses.

AUGUST NOGAR.
